CLAIM

The ornamental design for a sensor, as shown and described.

DESCRIPTION

FIG. 1 is a front-top perspective view of a sensor illustrating our new design.

FIG. 2 is a rear-bottom perspective view of a sensor illustrating our new design.

FIG. 3 is a front view of a sensor illustrating our new design.

FIG. 4 is a side view of a sensor illustrating our new design.

FIG. 5 is a top view of a sensor illustrating our new design; and,

FIG. 6 is a bottom view of a sensor illustrating our new design.

The broken lines in the drawings represent unclaimed environment only and form no part of the claimed design.
